Primary Examiner — Austin Murphy(74) *Attorney, Agent, or Firm* — Howard & Howard
Attorneys PLLC(57) **CLAIM**

I claim the ornamental design for a pen-shaped ambidextrous mouse, as shown and described.

DESCRIPTION

FIG. 1 is a perspective view of a pen-shaped ambidextrous mouse;

FIG. 2 is a front plan view of the pen-shaped ambidextrous mouse;

FIG. 3 is a rear plan view of the pen-shaped ambidextrous mouse;

FIG. 4 is a right side plan view of the pen-shaped ambidextrous mouse;

FIG. 5 is a left side plan view of the pen-shaped ambidextrous mouse;

FIG. 6 is a top plan view of the pen-shaped ambidextrous mouse; and,

FIG. 7 is a bottom plan view of the pen-shaped ambidextrous mouse.

The broken lines shown in the figures are for illustrative purposes only and form no part of the claimed design.
